UNITED STATES PATENT OFFICE.

JOHN W. GOODERHAM, OF YONKERS, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 19, 1921. Serial No. 508,711.

To all whom it may concern:

Be it known that I, JOHN W. GOODERHAM, a citizen of the United States, residing at Yonkers, in the county of Westchester, State of New York, have invented certain new and useful Improvements in Telephone-Exchange Systems, of which the following is a full, clear, concise, and exact description.

10 This invention relates to telephone exchange systems and particularly to an arrangement for making observations on the service afforded subscribers' lines in the establishment of calls.

15 In exchange systems where machine switching apparatus is employed at the central offices for setting up connections, it is desirable to take observations, from time to time, to ascertain the manner in which 20 the apparatus is functioning and to determine the quality of service being given the subscribers. Such information is not only of interest to the telephone company in showing the performance of the automatic 25 switching equipment, but also serves to definitely ascertain whether complaints entered by the subscribers against the quality of the service are due to failures in the apparatus or because of an improper usage by the subscriber of his telephone instrument, or for 30 any other reason.

In order that this information may be readily and conveniently obtained, a special desk is provided in the central office and equipped with apparatus and circuits for taking all the required observations on subscribers' lines. The observing operator presiding over the desk may inspect the operation of all switching mechanism involved in the extension of any particular subscriber's line responsive to the origination of a call thereon. The observing equipment is arranged to be associative with any suitable variable number of lines at a time and when thus allotted it serves to enable observations on any calling line in such group. To avoid mistakes, which might arise by interference in the association of the equipment with lines calling simultaneously, the arrangement is such that only one line of the group can be connected to said equipment at a time. When all notations have been taken with respect to a given line the observer's apparatus is released and thereafter may again be con-

nected to some other line in the group. From the nature of the tests made on a line, it is essential that the observing operator's equipment be associated with the line from the beginning of the call.

60 An object of the present invention is, therefore, to insure that an operator's position, when disconnected from one subscriber's line at a time subsequent to the initiation of a call on another line, cannot be connected to such other line.

Another object of the invention is to enable the taking of certain information at the operator's position regarding the transmission of impulses over the line and to 70 signal the operator whenever such impulses are improperly transmitted.

A feature of the invention relates to the provision of means, in an arrangement where the operator's equipment is automatically connected to a line on the initiation of a call, for delaying the connection of such equipment with another line following its disconnection from a given line until the time when no call exists on any of the lines.

80 Other and further features contemplated by the invention will be considered in detail hereafter.

Referring to the drawing, forming a part of this application, Figs. 1, 2 and 3 when arranged with Fig. 3 below Fig. 1 and Fig. 2 to the left of Fig. 3, illustrate a portion of an automatic telephone exchange to which the circuits and apparatus embodying the principles of the present invention are adapted.

Fig. 1 shows, in the upper portion thereof, a subscriber's line incoming to the central office from when it extends through the distributing frames to an individual line switch. There is also diagrammatically illustrated a trunk leading from the line switch to a first or district selector, a register sender for controlling selections and a trunk outgoing from the district selector. 95 In the lower part of this figure a similar showing is given of a subscriber's line incoming to the central office, with the exception that in this case line finder switches are used instead of individual line switches for extending calling lines to the district switches. In both modifications of the switching apparatus, as shown in Fig. 1, there is further illustrated an arrangement whereby connections may be made with sub- 100 105 110

scribers' lines for observation purposes by means of plugs and jacks, the plug circuits being attachable to the line conductors at the distributing frames.

Fig. 2 shows an observing operator's position at which there is located the necessary devices for taking observations of the service on calling lines.

In the space set off by the broken lines in the upper right-hand corner of Fig. 3, there are shown the several elements individual to one of the connecting circuits leading from the jacks shown in Fig. 1 to the observing operator's position. In the small rectangle to the left thereof are shown a few of the corresponding elements individual to a second one of these connecting circuits. In the remaining portion of the figure, the circuits and relays common to all connecting circuits are illustrated. Moreover, in addition to being applicable to the two classes of systems above mentioned, both of which involve central office controlled power driven switches, the observing apparatus is also applicable to systems of the step-by-step character.

Although the invention is applicable to other types of systems, the present disclosure shows its adaptation to a full mechanical system. Before describing the features of the operation of the observing apparatus shown in Figs. 2 and 3, an explanation will first be given of the machine switching mechanism serving the subscribers' lines on which the service observations are to be made. As was mentioned above, either individual line switches, such as line switch 128, or line finders, such as the finder 132, may be employed for extending the calling subscriber's line through to a district selector switch. The district selector 130, shown in connection with a subscriber's line served by an individual line switch and the similar district selector switch 134 shown in connection with lines served by line finders, may be of the power driven type in which the selection of brushes and the movement thereof into engagement with the desired outgoing circuits are accomplished by means of applying a constantly driven element to the movable member of the switch. The structure and operation of switches of this general character are shown and described in detail in the patent to E. B. Craft and J. N. Reynolds, No. 1,123,696, issued January 5, 1915. The selective movements of the district switches and also of succeeding switches in the establishment of the connection are controlled by means of the re-verteive impulse register senders diagrammatically shown at 131 and 135. These senders are of the usual type used for controlling power driven switches and receive the record from the calling subscriber's dial which later serves to govern the directive

movement of the switches. A register sender of the character suitable for use in controlling the switches illustrated in the present system is described in detail in the Patent 1,395,977, issued to F. A. Stearn and F. J. Scudder, November 1, 1921.

The subscriber's line A, which is one of a plurality of lines terminating in the multiple contacts of the line finder 132 on entering the central office, is first directed to the main distributing frame MDF. From here it leads to the terminal racks of the intermediate distributing frame IDF. Between the main and intermediate frames the subscriber's line is directed through the heat coils 126 which act as a protection against heavy currents. At the intermediate distributing frame, the line is connected and distributed to the desired terminals in the bank of the line finder switch. When it is desired to make observations on the subscriber's line A, the heat coils 126 are removed and a spring connecting plug 125 is inserted as shown. The plug switch 125 is the terminating end of a pair of cord circuits 149, 150 and 147, 148. These connecting cords at their other ends terminate, respectively, in the plugs 122 and 123. A third connecting cord 156, 157 terminating in the plug 124 is connected to the proper terminals at the intermediate distributing frame by any suitable means such as a shoe 127. To complete the association of the line A with the observing position, the plugs 122, 123 and 124 are inserted, respectively in the jacks 119, 120 and 121 provided at some convenient location in the vicinity of the distributing frame. From the jacks 119, 120 and 121 the connecting circuit, comprising conductors 102, 103, 104, 105, 106 and 107, leads to the individual apparatus shown in the upper right-hand corner of Fig. 3. In this manner the line A is connected through to the operator's position and the individual apparatus is now allotted for the sole use of this particular line. In like manner any desired number of other lines similar to line A may be extended to the corresponding individual mechanisms at the observing operator's position by means of other plug and jack connectors. For example, a group of forty lines served by the line finder switches may be connected to the observing position at a time whereby the observing operator may take notations of the service being rendered on these lines.

Where subscribers' lines, such as B shown in the upper part of Fig. 1, are served by line switches, the extension of the lines through the main and intermediate frames is substantially the same although the method of connecting the line to the observing position differs somewhat. For example, the heat coils are not removed but the entire connection is made at the intermediate dis-

tributing frame by means of the cords which terminate in plugs 112, 113, 114 and 115. The first three cords are attached as illustrated to the proper connecting points on the intermediate distributing frame by shoes 116 and 117, while the cord terminating in plug 115 is attached to the back contact of the line relay by a suitable attachment clip. The same is true of lines which terminate in individual switches, namely, that any desired number thereof may be connected to the observing position at a time.

The equipment at the operator's desk includes a talking set comprising a receiver 200 (Fig. 2) and a transmitter 229 and a plug and jack switch 201 for rendering the equipment effective. By means of his talking set the operator may converse with a calling subscriber whose line has been connected to his position. Furthermore, there are provided two cycle counters 213 and 225. These devices may consist of any well known mechanism responding to an alternating current and which serves to drive a counting member through one step for each cycle through which the current passes. For operating the cycle counters, there is provided a driving fork 215 which may be adjusted to operate at any desired frequency. The frequency of the driving fork will determine by means of an induction coil 214, the frequency set up in the secondary circuit, and consequently, the frequency of the current flowing through the cycle counters. In an obvious manner the distance through which the movable element of the cycle counter moves in response to a current of known frequency, may indicate the exact amount of time elapsing from the instant the counter is started in operation until the operation ceases. The principle of such devices is an old and well known one for obtaining an accurate measurement of time. The cycle counter per se is not concerned particularly with the present invention and, therefore, it is not considered necessary to describe its operation and mechanism in detail. It is merely one device for obtaining an accurate measurement of the time required for certain operations in the system to take place. Any other time measuring device might be used equally as well provided it gave the required degree of accuracy. The cycle counter 213, as will be hereinafter described, is used for counting the time elapsing from the instant the subscriber initiates a call until a sender is attached to his line ready to receive impulses. The cycle counter 225 is used for counting the time between the initiation of the call and the instant when the first impulse is sent from the substation.

In addition, the operator's desk is equipped with a pen register mechanism consisting of a magnet 208, the armature of

which carries a pen arranged to engage a moving tape 230 to record the nature of the impulses sent out over the calling line.

Certain other devices to be described hereinafter are also located at the operator's position for making observations of message registration and coin operations.

The system in general and the apparatus involved therein having been outlined above, a description will now be given of the detailed operation. To this end it is assumed at first that the observing operator wishes to inspect the service being rendered on a certain group of subscribers' lines served by line finder switches. To do this, the operator removes the heat coils 126 of each line and connects such line, as hereinbefore explained, to the connecting circuit leading to the observing desk by means of the plug ended connecting cords. Since the identity of each of the several connecting circuits is known, the identity of the lines to which they are made individual, respectively, is also readily determined.

After having connected up a group of lines on which the service is to be inspected, the observing operator renders his equipment effective for association with any line in the group that calls by completing the plug and jack connection 201. The insertion of these plugs in the jacks extends the conductor 204 over the spring contacts 203 to conductor 231. The conductor 231 leads through the upper contact of relay 232 to ground through the left normal contact of release key 209. The conductor 204 extends over parallel paths to the inner armatures of each of the several relays 300, only one of which is shown. There is a relay 300 individual to each connecting circuit, and consequently, individual to the particular subscriber's line associated with the operator's position by means of such connecting circuit. The relay 300 corresponds to the line relay and energizes at the same instant the line relay is operated. Whenever one of these relays operates, it connects the common conductor 204 through its armature and contact to the winding of an individual relay such as relays 302 and 303 as will presently be described. With the apparatus thus in condition to make observations, it is now assumed that the subscriber of line A initiates a call.

Upon removing his receiver from the switch-hook, the subscriber of line A closes a circuit from battery, through the winding of line relay 152, inner left contact of relay 151, through the intermediate distributing frame, lowermost contact of plug 125, conductor 150, sleeve of plug 122, sleeve of jack 119, conductor 105, winding of relay 300, conductor 103, sleeve of jack 120, sleeve of plug 123, conductor 148, next to lower contact of plug 125, conductor 146, 130

- over the loop of the subscriber's line and returning by way of conductor 145, next to the upper spring of plug 125, conductor 147, tip of plug 123, tip of jack 120, conductor 102, 5 conductor 360, conductor 104, tip of jack 119, tip of plug 122, conductor 149, uppermost spring of plug 125, through the intermediate distributing frame, to ground at the right contact of relay 151. The line relay 10 152 becomes energized in this circuit and in the well known manner causes the line finder 132 to start in operation, searching for the subscriber's line. The line finder 132 may also be of the panel power driven 15 type provided with a plurality of sets of brushes arranged to be tripped when operated in the manner described in the patent to J. L. McQuarrie, No. 1,177,044, patented March 28, 1916.
- 20 At the same instant relay 152 energizes, the relay 300, also included in series therewith, attracts its armatures. The relay 300 extends the common conductor 204 through its inner armature and contact, inner back 25 contact of relay 304, outer contact of relay 305, right-hand winding of relay 302, make-before-break contact at the left-hand armature of relay 306, winding of relay 307, to battery. The individual relay 302 30 and the common relay 307 become operated in this circuit. Relay 302 closes a holding circuit for itself traceable from battery, through the left-hand winding and inner left front contact of said relay, winding of 35 relay 306, conductor 210, right contact of key 209, to ground. Relay 306 energizes in series with the locking circuit of relay 302 and opens the original energizing circuit of relay 302 which included the winding 40 of relay 307. Relay 307, however, remains energized in a circuit from battery, through its winding, the make-before-break contact at the left armature of relay 306, thence to ground over conductor 210. Relay 45 302 closes a circuit from battery, through the winding of relay 305, inner left front contact of relay 302, and thence to ground over the conductor 210 as previously traced. Relay 305 operates and creates 50 a second break point in the original energizing circuit of relay 302. In parallel to the relay 305, relay 302 completes a circuit for the lamp 301 which is individual to the connecting circuit, and consequently, 55 individual to the calling line A. The lamp 301 illuminates and advises the operator that a call has been initiated on this particular line.
- The relay 302, furthermore, extends the 60 circuit 308, 309 leading from the operator's talking set by way of conductors 102 and 103 through to the subscriber's line conductors 145 and 146. In other words, the energization of relay 302 causes the extension of the line A to the observing opera- 65
- tor's telephone equipment, whereby conversation may be held between the subscriber and the operator. Another result of the energization of relay 302 is the closure of a circuit for relay 322. This circuit may 70 be traced from battery, through the windings of relay 322, left contact of relay 323, conductor 309, inner right front contact of relay 302, conductor 103, sleeve of jack 120, sleeve of plug 123, conductor 148, next to 75 the lower contact of plug 125, conductor 146, thence over the line A, returning by conductor 145, next to the upper spring of plug 125, conductor 147, tip of plug 123, jack 220, conductor 102, outer right contact of relay 302, conductor 308, right contact of relay 323, to ground. Relay 322 operates and completes a circuit from battery, through the left-hand winding of relay 324, contact of relay 322, left and back 80 contact of relay 314, conductor 210, to ground at key 209. Relay 324 operates and closes a circuit from battery, through the winding of relay 325, inner left contact of relay 324, left back contact of relay 314, 85 to ground over conductor 210. Relay 325, upon energizing, closes a circuit from battery, through its winding and right contact, winding of relay 314, conductor 210, to ground. Relay 314, however, cannot energize in this circuit since it is shunted out by the direct circuit to ground previously traced through the winding of relay 325 and inner left contact of relay 324. Therefore, as long as relay 324 remains operated, 90 the relay 314 is held shunted and cannot become energized. Relay 325 also closes a circuit from battery, through the winding of relay 326, left contact of relay 325, to ground over conductor 210. 95
- With relays 300 and 302 operated, a circuit is closed from ground, over conductor 204, inner contact of relay 300, outer left contact of relay 302, conductors 311 and 327, left back contact of relay 328, winding 100 of relay 329, to battery. Relay 329 operates and completes a circuit from battery, through its winding and the winding of relay 328 in series, right contact of relay 329, to ground by way of conductor 210. Relay 328, 105 however, cannot energize since it is shunted out by the direct circuit to ground traced through the contacts of relays 300 and 302.
- The observing equipment at the operator's 110 equipment is now connected to the subscriber's line A, which connection has taken place instantly in response to the initiation of a call on said line. Should another line in the group associated with the operator's 115 position by means of the plug and jack connections originate a call at any time during the connection of the position with the line A, provision is made whereby said second line will be ineffective to cause the con- 120
- 125
- 130

nection of the operator's position thereto. This end is accomplished by rendering all remaining relays 303, etc., which are individual to the other lines in the group inoperative in response to the energization of their corresponding relays 300. From inspection of the drawing, it will be seen that the energizing circuit through the right-hand winding of relay 302 extends from 5 battery, through the winding of relay 307 and over the make-before-break contact of relay 306. The conductor 330 leading from the contact of relay 306 is multiplied to the operating winding of all relays 302, 303, etc. Since the relay 302 is energized and the common relay 306 is also operated, the conductor 330 is opened at the make-before-break contact of the said latter relay and, hence, no other relay 303, etc., can have its 10 operating circuit closed due to the initiation of a call of the line to which it is individual.

At the instance the relay 307 attracts its armatures, circuits are closed for supplying 15 alternating current to the cycle counters 213 and 225 in order that these devices may commence to count time from the initiation of the call. The circuit for counter 213 may be traced from battery, through the tip 20 of jack 211, tip of plug 212, thence through the counter 213, sleeve of plug 212, sleeve of jack 211, through the right-hand winding of coil 214, conductor 216, lowermost contact of relay 217, conductor 218, outer 25 contact of relay 307, inner right contact of relay 312, conductor 313, sleeve of jack 219, sleeve of plug 220, through the counter 213, tip of plug 220, tip of jack 219, to ground. The circuit for applying current to the 30 other counter 225 may be traced from battery, through the tip of jack 223, tip of plug 224, through the counter 225, sleeve of plug 224, sleeve of jack 223, thence through the right-hand windings of coil 214, conductor 40 216, lowermost contact of relay 217, conductor 218, outer contact of relay 307, right contact of relay 314, conductor 315, sleeve of jack 227, sleeve of plug 226, through the counter 225, tip of plug 226, tip of jack 227, 45 to ground.

As soon as the line finder switch 132 advances its brushes onto the terminals of the calling subscriber's line A, a circuit is completed in the usual well known manner for the energization of the cut-off relay 151. This circuit leads from a source of battery current over the next to the lower brush and contact of finder 132, through the winding of relay 151, to ground. A parallel circuit 50 is also closed through the intermediate distributing frame to conductor 156, tip of plug 124, tip of jack 121, conductor 106, the manual switch 321 in its position shown, conductor 319, manual switch 318, through 55 the winding of relay 317 to ground.

It may be noted at this point that when the observing equipment is employed for taking observations on lines which are served by line finder switches, the switch 321 is in the position indicated, the switch 70 331 is opened and the switch 332 is closed as indicated. These switches are ordinary manual devices adjusted by the operator.

The cutoff relay 151 opens the circuit of the line relay 152 and also the circuit of relay 300. Relay 317, upon energizing, closes a circuit for the slow relay 304. When relay 300 becomes deenergized, it opens the shunt around the winding of relay 328 and this relay operates in series with relay 329. Relay 328 closes a circuit for the illumination of lamp 333, notifying the observer that the subscriber's line has been found.

When the subscriber's line is extended to an idle register sender 135, the sender selector having chosen an idle sender in the manner set forth in the above-mentioned patent to F. A. Stearn and F. J. Scudder, No. 1,395,977, issued November 1, 1921, the impulse relay of the selected sender is connected in circuit with the subscriber's line including the individual relay 300 of the observing equipment. This circuit leads from battery through the winding of the impulse relay (not shown) in the register sender 135, left-hand contact of spring 160, next to the upper brush of the line finder 132, through the intermediate distributing frame, lowermost spring of plug 125, conductor 150, through the plug 122 and jack 119 to conductor 105, winding of relay 300, conductor 103, through the jack 120 and plug 123, conductor 148, next to the lower spring of plug 125, over the loop of the subscriber's line, next to the upper spring of plug 125, conductor 147, through the plug 123 and jack 120 to conductor 102, conductor 360, conductor 104, through the jack 119 and plug 122 to conductor 149, thence 100 through the intermediate distributing frame, through the uppermost brush of the finder 132, lower left contact of spring 161 and thence to ground at the register sender 135. Relay 300 again operates in the circuit traced and completes a circuit from 105 ground over conductor 204, inner contact of relay 300, outer left contact of relay 302, conductors 311 and 327, left front contact of relay 328, contact of relay 362, winding of relay 312 to battery. Relay 312 operates 110 and completes a circuit from battery through its winding and the winding of relay 362 in series, left contact of relay 312, conductor 363, left normal contact of key 209, to ground. Relay 362, however, cannot 115 operate in this circuit since it is shunted by the circuit closed through the contact of relay 300. Relay 312 upon attracting its armatures opens the circuit previously traced over conductor 313 for the flow of current 120 125 130

through the cycle counter 213. The cycle counter 213 thereupon ceases its operation, having measured the time elapsing between the initiation of the call on the subscriber's line, and the instant when an idle register sender 135 becomes attached to such line ready to receive impulses transmitted from the subscriber's dial. The reading from this counter may be taken at any desired time by the observer. Relay 312 also closes a circuit from battery through the winding of relay 335, outer right contact of relay 312 to ground over conductor 210. Relay 335 serves to prevent the closure of the circuit of relay 336 for a purpose which will become obvious hereinafter.

It will be recalled that the relay 322 was connected in the subscriber's line A at the time relay 302 became energized. When, following the original energization of relay 322, the subscriber's line is extended to the register sender 135 and the impulse relay thereof is included in series with the calling line, the flow of current through the relay 322 becomes diminished sufficiently to permit the release of said latter relay. Relay 322 opens the circuit of the left-hand winding of relay 324, but this relay remains locked in a circuit from battery through its right-hand winding and right contact, conductor 364, right contact of relay 305, inner front contact of relay 304, inner contact of relay 300 to ground over conductor 204. Therefore, relay 324 is not permitted to deenergize and remove the shunt around the winding of relay 314 at the time relay 322 becomes deenergized. Immediately that the relay 312 operates, which occurs soon after the extension of the subscriber's line to the register sender, a circuit is closed from battery through the right-hand winding of relay 323, outer right contact of relay 312 to ground over conductor 210. Relay 323 operates and disconnects the relay 322 from the conductors 308 and 309 to prevent the reenergization of said latter relay. Relay 312 also closes a circuit from battery through the lamp 334, outer right contact of relay 312 to the grounded conductor 210. The lamp 334 advises the operator that an idle register sender has been seized.

It is assumed that the subscriber at substation A has allowed a sufficient time for the apparatus at the central office to associate a sender with his line following the initiation of the call. He then manipulates his dial to transmit the first series of impulses corresponding to the wanted designation. Upon the first opening of the line by the impulse sender, the relay 300 becomes deenergized and opens the shunt around the winding of relay 362 and also opens the holding circuit of relay 324. Relay 362 operates in series with relay 312 and

locks to the grounded conductor 363 over the circuit previously traced. The relay 324 upon releasing its armatures opens the shunt hereinbefore described around the winding of relay 314. Relay 314 thereupon operates in series with relay 325 and locks to ground over the conductor 210. The relay 314 at its right-hand armature opens the circuit over conductor 315 for supplying current to the second cycle counter 225. This counter thereupon ceases to operate having accurately measured the time elapsing between the initiation of the call and the instant when the first impulse was transmitted by the subscriber.

If the observer wishes to take a record of the impulses transmitted by the calling subscriber, he may do so by inserting the plug 207 in the jack 206. At the time relay 302 first became operated, a circuit was closed for relay 233 traceable from battery through the winding of this relay, conductor 311, outer left contact of relay 302, conductor 310, inner contact of relay 300 to ground over conductor 204. Relay 233 operates and closes a circuit from battery through the winding of relay 205, front contact of relay 233 to ground through the left normal contact of key 209. Relay 205 operates and locks in a circuit from battery through its winding and left contact and contacts of key 234 to ground at key 209. When impulses are transmitted by the subscriber, the relay 300 operates in response thereto and in so doing causes the corresponding operation of relay 233. For each deenergization of the relay 233, a circuit is closed from battery through the sleeve of jack 206, sleeve of plug 207, winding of the pen register magnet 208, tip of plug 207, tip of jack 206, right contact of relay 205, back contact of relay 233 to ground at the release key 209. The magnet 208 attracts its armature and presses the pen against the moving paper 230 thereby producing a graph of the impulse series.

Assume that the calling line is one on which a coin box is located. In this case coin collect or refund current will be applied to the line at some time during the release of the connection in the usual manner. It is desirable that the observing operator be notified with respect to the operation of the coin box both as regards the character of the current applied and also the time and duration thereof. For this purpose, the lamps 235 and 236 are provided, one of which signifies that coin collect current is being applied to the line, while the other signifies that refund current is being sent over the line. If the call succeeds, a source of collecting current is applied and in addition to flowing over the subscriber's line, it also flows over the tip conductor through the intermediate distributing frame, thence

as heretofore traced over the conductor 102, outer right contact of relay 302, conductor 308, winding of relay 237, winding of polarized relay 238, to ground. Relay 237 operates, but the polarity of the current is such that the polarized relay 238 remains inert. Consequently, a circuit is closed from battery through the winding of relay 239, lamp 236, back contact of relay 238, to ground 5 at the front contact of relay 237. The lamp 236 notifies the operator that collecting current is being applied to the subscriber's line. In order that the observer's attention may be attracted at this time, the relay 239, on 10 energizing, completes a circuit for the buzzer 240. If, on the other hand, refund current is applied, its polarity being of an opposite character, both relays 237 and 238 are operated. In this event, a circuit is 15 closed from battery through the winding of relay 239, lamp 235, front contacts of relays 238 and 237 to ground, causing the illumination of the lamp 235.

Should the calling subscriber's line A be 20 one which is equipped with a message register, it is also desirable that the observer be aware of the fact that the register is operated properly. At the time of disconnection, if the call proved to be successful, 25 a message register source of current is applied in the usual manner over the lowermost brush of the finder switch 132, contact of the line relay 152, through the intermediate distributing frame, winding of the 30 message register 158, thence over two parallel branches, one of which leads back through the distributing frame through the left front contact of the cut-off relay 151 and to ground, and the other of which extends over conductor 157, sleeve of plug 124, sleeve of jack 121, conductor 107, inner left contact of relay 305, conductor 316, through the winding of relay 228 to ground. Relay 228 operates and closes a circuit from 35 battery through the winding of relay 239, lamp 241, to ground at the contact of relay 228. The lamp 241 and the buzzer 240 advise the observer that the message register of the calling line has been properly operated. 40

After having completed his observations 45 on the subscriber's line A, the operator may disconnect the equipment at his desk from said line, in order to render it connectible to some other line in the group by manipulating the release key 209. Upon operating the key 209, ground is removed from the conductors 210 and 363 thereby permitting relays 302, 306, 307, 305, 328, 329, 362, 312, 326, 314, 325 and 323 to become deenergized. The release of these relays also causes the extinguishment of the lamps 301, 333 and 334. The operation of key 209 also opens the holding circuit of relay 205.

50 It will next be considered that the sub-

scriber commences to manipulate his impulse transmitter too soon, that is, prior to the time that a register sender 135 has been seized and placed in condition to receive impulses. It will be recalled that the relay 300 is deenergized during the interval between the instant that the subscriber's line has been found by the line finder switch 132 and the instant that an idle register sender is attached with the mechanism. In 70 this condition, the relays 322, 324, 325, 329 and 328 are operated, but relays 312, 362, 314 and 335 are still deenergized. When, therefore, the first impulse is transmitted the opening of the calling line also severs 75 the circuit of relay 322 and this relay becomes deenergized. Relay 322 opens the circuit for the left-hand winding of relay 324, and this latter relay becomes deenergized since the previously traced holding circuit through its right-hand winding is now opened due to the fact that the relay 300 is deenergized. Consequently, relay 80 324 retracts its armatures and opens the shunt circuit around the winding of relay 85 314. Relay 314 thereupon energizes in series with relay 325 and in so doing opens the circuit of the second cycle counter 225 to give a measurement of the time elapsing 90 between the initiation of the call and the instant the subscriber commences to dial. Since the relay 312 has not operated due to the fact that a sender was not yet attached, the relay 335 is still inert and hence the release of relay 324 causes the closure of a 95 circuit from battery through the winding of relay 336, contact of relay 335, outer left contact of relay 324, left contact of relay 325 to ground over conductor 210. Relay 100 336 operates and locks through its winding and contact to the grounded conductor 363. Relay 336 closes a circuit from battery through the lamp 337, contact of relay 336, conductor 363 to ground. The illumination of lamp 337 notifies the observer that the 105 calling subscriber has commenced to manipulate his dial prematurely. He may communicate, if desirable, with the subscriber and explain to him that more time 110 should be allowed following the removal of the receiver before the dial is operated. Disconnection of the observing equipment from the subscriber's line takes place in the same manner as above explained by the depression of the release key 209.

115 A description will now be given of the arrangement provided for making it impossible for the observing operator's equipment to become connected to a second subscriber's line when said equipment is released from a first subscriber's line at any time subsequent to the initiation of a call on said second line. It is obvious that the operator's equipment should be associated 120 with the line as soon as the call is initiated,

since it is necessary to measure the time elapsing from the instant of initiation until the line has been found in the one case and until a sender has been attached in the other. 5 Should the equipment be connected to a line after a call had partly progressed, the readings taken by the counters would not give the exact information required. Therefore, the circuits are so arranged that when 10 the operator depresses the release key and releases the equipment from one subscriber's line at a time a call has partly progressed on some other line, the equipment cannot be associated with said second line and 15 neither can it be associated with any line until the time arrives when there is no call existing on any line. This precaution insures that the equipment when once attached to a line will be in condition to enable the proper observations of the service 20 thereon. Assume, now, that the observing equipment has been attached to the line A in the manner already explained and the operator desires to disconnect the same 25 therefrom and depresses the key 209 at a time when a call has partly progressed on some other line with which the observing equipment is temporarily associated.

It will be noted that the conductor 204 is 30 connected through the contacts 203 of the jacks 201 to conductor 231 whence it extends over two parallel branches, one of which may be traced as hereinbefore explained through the contacts of key 209 and the 35 other branch through the winding of the relay 202. The relay 202 is shunted out so long as the key 209 remains in its normal condition. Therefore, the operation of the relay 300 at the time a call is initiated completes the conductor 204 through the winding 40 of relay 202 as traced to battery, but relay 202 being shunted by the release key does not operate in series with the relay 302. When, however, the operator depresses the key 209 to release the equipment, a circuit 45 is closed from battery through the winding of relay 232, left alternate contact of key 209 to ground. Relay 232 operates and at its upper armature opens the shunt circuit 50 around the winding of relay 202. At this particular instant, since a second line is calling, the relay 300 individual to said line is energized and is extending a second branch of the common conductor 204 through to the 55 right-hand winding of relay 303, which it may be assumed, is the relay individual to the said second line. This circuit after passing through the right-hand winding of relay 303 is then traceable through the make-before-break contact of relay 306 and the winding 60 of relay 307 to battery, the relay 306 becoming deenergized immediately upon the operation of the key 209. This modified circuit through the operating winding of relay 303 and the winding of relay 307, how-

ever, includes the resistance of relay 202 which is comparatively high. Relay 202 operates, but its resistance being of such a high value prevents the operation of relays 303 and 307. Hence, since the relay 303 70 cannot be operated, the operators' equipment cannot be connected to the subscriber's line to which said relay is individual, notwithstanding the fact that a call has been initiated thereon. The relay 202, in operating, closes a locking circuit for relay 232 in order to maintain this latter relay energized after the key 209 is released. This condition prevails until the relay 300 of the second calling line becomes deenergized, say, at the 80 time the line finder finds the line. When the corresponding relay 300 releases it opens the circuit through the winding of relay 202 and this relay becomes deenergized to open the circuit of relay 232. Relay 232, on de-energizing, recompletes the low resistance shunt around the winding of relay 202. When now the line relay corresponding to relay 300 individual to the second calling line again operates at the time a register 85 sender is attached, the conductor 204 is ex- 90 tended through the inner contact thereof, but still the circuit for the right-hand winding of relay 303 cannot be completed due to the fact that the relay corresponding to relay 304 individual to the line has been energized. Relay 304 is energized following the energization of relay 317 which occurs as heretofore explained at the time the line is 95 found.

Should it so happen that a third subscriber's line has a call in progress thereon at the time the line finder finds the second calling line, the circuit arrangement is so taken that the operator's position cannot be 100 associated with this third line. When the finder finds the second line, as explained, the individual relay 300 releases and opens the circuit including the winding of relay 202 and the right-hand winding of the connecting relay 303. Relay 202, however, cannot 105 become deenergized since its circuit is closed over another parallel branch which leads in a similar manner through the contact of the relay 300 belonging to the third calling line, the right-hand winding of the relay 303 individual to such line, and thence through the winding of relay 307. The same condition is true with regard to as many lines as 110 have calls co-existing thereon following the time that the operator's equipment is released from one subscriber's line at the instant a call exists on another line. In other words, the equipment cannot be connected except at an instant when there is no call 115 already existing on any line.

When it is desired to associate the equipment with subscribers' lines served by line switches, the connections are made, as illustrated, in the upper part of Fig. 1. In ad- 120

dition to connecting the different terminals on the intermediate distributing frame with the connecting circuit to the operator's position, it is necessary in this case to disconnect the tip and ring straps 165 and 166. This may be accomplished by unsoldering these straps on one side of the frame.

When the subscriber of line B initiates a call a circuit is closed in the usual manner for the line relay 118 and may be traced from ground through the left-hand winding of said relay, left contact of cut-off relay 142, conductor 140, tip of plug 112 and jack 108, conductor 104, conductor 360, conductor 102, tip of jack 109 and plug 113, thence over the line conductor 136, returning by way of conductor 137, conductor 144, sleeve of plug 113 and jack 109, conductor 103, winding of relay 300, conductor 105, sleeve of jack 108 and plug 112, conductor 141, inner right contact of relay 142, right winding of relay 118 to battery. The line relay 118 operates and initiates the movement of the line switch 128 in the usual manner.

In response to the energization of relay 300, the same series of operations occur at the operator's equipment as described in connection with the line A. Relay 302 is operated, and in turn starts the energization of relays 306, 329, 305, 322, 324, 325 and 326. As soon as individual line switch 128 takes its first step, the off-normal contact 167 is closed, completing a circuit from ground through said contact, conductor 153, tip of plug 115 and jack 111, conductor 106, thence through the manual switch 321, (which is now thrown to its alternate position) winding of relay 304, to battery. One point of difference over the preceding operation to be noted in the present instance is that the relay 304 is operated immediately that the line switch commences its operation, whereas in the case of a subscriber's line served by a line finder switch, this relay does not operate until the line has been found.

When the line switch 128 finds an idle trunk leading to a district selector switch 130, the cut-off relay 142 is operated, thereby disconnecting the line relay 118 and also opening the circuit of relay 300. In response to the deenergization of relay 300, the same operations occur at the observer's desk as previously explained. Relay 328 is operated and lamp 333 illuminated, notifying the operator that a district switch has been selected. When, subsequently, an idle register sender 131 is attached, the relay 300 becomes energized as hereinbefore described, causing the actuation of relay 312 and the stopping of the cycle counter 213. In response to the first impulse sent out by the calling subscriber's dial, relay 314 becomes operated and the second cycle counter 225 is arrested.

If the subscriber's line B is one provided with a message register, metering current is applied at a suitable time over a circuit leading through the lowermost brush of the line switch 128, thence through the intermediate distributing frame, winding of the message register magnet 154, through the outer right contact and right-hand winding of relay 142 to ground. In parallel with this circuit a branch leads from the terminal of the intermediate distributing frame, thence over conductor 155, sleeve of plug 114 and jack 110, conductor 107, inner left contact of relay 305, conductor 316, winding of relay 228, to ground. Relay 228 causes the illumination of lamp 241 to notify the operator that the message register is being operated.

All other operations are substantially the same as hereinbefore described in detail in connection with the observation made on the subscriber's line A.

When the observing equipment is used to make observations on subscribers' lines in a step-by-step switching system, the connection of the equipment may be made in substantially the same manner as shown in the lower part of Fig. 1 by use of cord circuits which lead from the main distributing frame to the jacks provided for this purpose. The heat coils at the main distributing frame are removed as in the case previously explained. The circuits and apparatus shown in Fig. 3 respond to the operation of the line switches during the extension of the subscriber's line in the step-by-step system, during the initiation of a call for controlling the observing devices at the position shown in Fig. 2 in substantially the same manner as already described in detail.

In case of observations made on subscribers' lines in a step-by-step system, the cycle counter 213 would serve to measure the time from the initiation of the call to the instant when the subscriber's line had been extended to a first selector switch ready to receive impulses. The cycle counter 225 would be employed for taking a measurement of the time elapsing between the initiation of the call and the instant when the subscriber operates his dial. It will be obvious how the pen register mechanism, the message register signals and the other elements associated with the observer's desk are operated to give the same records and indications for a subscriber's line in a step-by-step system as for the lines A or B terminating in an office where power driven switches are involved.

What is claimed is:

1. In a telephone system, a plurality of lines, an operator's position, means for connecting the operator's position to one of said lines, means for connecting the operator's position to a second line, and means for rendering said last connecting means ineffec-

tive when the operator's position is disconnected from the first line subsequent to the initiation of the call on said second line.

2. In a telephone system, a plurality of lines, an operator's position, means for connecting the operator's position to one of said lines, means for disconnecting the position from said line, means for connecting the operator's position to a second line, and means for rendering said last connecting means ineffective when the operator's position is disconnected from the first line subsequent to the initiation of the call on said second line.

3. In a telephone system, a plurality of lines, an operator's position common to said lines, means responsive to the initiation of a call on one of said lines for connecting the operator's position to such line, means for disconnecting the position from said line, means responsive to the initiation of a call on a second line for connecting the operator's position to said second line, and means for rendering said last connecting means ineffective when the operator's position is disconnected from the first line at a time subsequent to the initiation of the call on said second line.

4. In a telephone system, a plurality of lines, an operator's position common to said lines, means for connecting the operator's position to one of said lines, means for rendering said position non-connectible to more than one line at a time, means for disconnecting the position from said line, means responsive to the initiation of a call on a second line for connecting the operator's position to said second line, and means for rendering said last connecting means ineffective when said position is disconnected from the first line subsequent to the initiation of the call on said second line.

5. In a telephone system, a plurality of lines, an operator's position, means individual to one of said lines for connecting the operator's position to said line, means individual to a second line for connecting the operator's position to said second line, and means for rendering said last connecting means ineffective when the operator's position is disconnected from the first line subsequent to the initiation of the call on said second line.

6. In a telephone system, a plurality of lines, an operator's position, a connecting relay individual to one of said lines for connecting the operator's position to such line, means for disconnecting the position from said line, a connecting relay individual to a second line and responsive to the initiation of a call thereon for connecting the operator's position to said second line, and means for rendering said last connecting relay ineffective when the operator's position is disconnected from the first line subsequent

to the initiation of the call on said second line.

7. In a telephone system, a plurality of lines, an operator's position, means individual to one of said lines for connecting the operator's position thereto, means common to all of said lines for rendering the operator's position non-connectible to more than one line at a time, means for disconnecting the operator's position from said line, means individual to a second line and responsive to the initiation of a call thereon for connecting the operator's position to such second line, and means for rendering said last connecting means ineffective when the operator's position is disconnected from the first line subsequent to the initiation of the call on said second line.

8. In a telephone system, a plurality of lines, an operator's position, means controlled by the operator for rendering said position connectible to any of said lines, means for connecting the operator's position to one of said lines, means controlled by the operator for disconnecting the position from said line, means responsive to the initiation of a call on a second line for connecting the operator's position to such second line, and means for rendering said last connecting means ineffective when the operator's position is disconnected from the first line subsequent to the initiation of the call on said second line.

9. In a telephone system, a plurality of lines, an operator's position, means for associating said position with a group of said lines, said group containing any desired number of lines, means for connecting the operator's position to one of said lines, means for disconnecting the position from said line, means responsive to the initiation of a call on a second line for connecting the operator's position to such second line, and means for rendering the last connecting means ineffective when the operator's position is disconnected from the first line subsequent to the initiation of the call on said second line.

10. In a telephone system, a plurality of lines, an operator's position, an observing mechanism at said position for observing the service on said lines, means for connecting said mechanism to one of said lines, means for disconnecting said mechanism from said line, means responsive to the initiation of a call on a second line for connecting the observing mechanism to said second line, and means for rendering said last connecting means ineffective when the said mechanism is disconnected from the first line subsequent to the initiation of the call on said second line.

11. In a telephone system, a plurality of lines, an operator's position, means for automatically extending one of said lines, means

for connecting the operator's position to such line, means for disconnecting the position from said line, means responsive to the initiation of a call on a second line for automatically extending such line, means responsive to the initiation of the call on said second line for connecting the operator's position thereto, and means for rendering said last connecting means ineffective when the operator's position is disconnected from the first line subsequent to the initiation of the call on said second line.

12. In a telephone system, a plurality of lines, an operator's position, automatic switches responsive to the initiation of a call on one of said lines for extending such line, means responsive to the initiation of said call for connecting the operator's position to said line, means for disconnecting the position from said line, said automatic switches being responsive to the initiation of a call on a second line for extending such line, means responsive to the initiation of the call on said second line for connecting the operator's position thereto, and means for rendering said last connecting means ineffective when the operator's position is disconnected from the first line subsequent to the initiation of the call on said second line.

13. In a telephone system, a plurality of lines, an operator's position, a plurality of automatic switches, means responsive to the initiation of a call on one of said lines for operating said switches to extend such line, means for connecting the operator's position to said line, means for disconnecting the position from said line, means responsive to the initiation of the call on a second line for operating the automatic switches to extend such second line, means responsive to the initiation of the call on said second line for connecting the operator's position thereto, and means for rendering said last connecting means ineffective when the operator's position is disconnected from the first line at a time when said second line has been partly extended.

14. In a telephone system, a plurality of lines, an operator's position, a plurality of automatic switches, means responsive to the initiation of a call on one of said lines for operating said switches to extend such line, means responsive to the initiation of said call for connecting the operator's position to said line, means for disconnecting the operator's position from said line, means responsive to the initiation of a call on a second line for operating the automatic switches to extend said second line, means responsive to the initiation of the call on said second line for connecting the operator's position thereto, and means for rendering said last connecting means ineffective when the operator's position is disconnected

from said first line at a time subsequent to the initiation of the call on said second line and before said second line has been completely extended.

15. In a telephone system, a plurality of lines, an operator's position, means responsive to the initiation of a call on one of said lines for automatically extending such line, means responsive to the initiation of the call on said line for connecting the operator's position thereto, means for disconnecting the position from said line, means responsive to the initiation of a call on a second line for automatically extending such second line, means responsive to the initiation of the call on said second line for connecting the operator's position thereto, means at said position for measuring the time required for the extension of said lines, and means for rendering said last connecting means ineffective when the operator's position is disconnected from the first line subsequent to the initiation of the call on said second line and before such second line has been extended to a certain point.

16. In a telephone system, a plurality of lines, an operator's position, means for connecting the operator's position to one of said lines, means for disconnecting the position from said line, means responsive to the initiation of a call on a second line for connecting the operator's position thereto, and means for delaying the connection of the operator's position to a second line until the time arrives following the disconnection of said position from the first line when no call exists on any line.

17. In a telephone system, a plurality of lines, an operator's position, means for connecting the operator's position to one of said lines, means for disconnecting the position from said line, means responsive to the initiation of a call on a second line for connecting the operator's position thereto, and means controlled by said disconnecting means for delaying the connection of the operator's position to a second line until the time arrives following the disconnection of said position from the first line when no call exists on any line.

18. In a telephone system, a line, an operator's position, means for extending said line, means for connecting the operator's position to such line, means for sending impulses over said line, means at the operator's position for measuring the time between the initiation of a call on said line and the instant when the same is extended to a certain point, and means for signaling the operator if impulses are sent over the line before such line has been extended to said point.

19. In a telephone system, a line, an operator's position, means responsive to the initiation of the call on said line for extending

the same, means for connecting the operator's position to such line, means for sending impulses over said line, means at the operator's position for measuring the time 5 between the initiation of the call and the instant when said line is extended to a certain point, and a signal lamp at the operator's position rendered effective if impulses are sent over the line before the same has 10 been extended to said point.

20. In a telephone system, a line, an operator's position, means for extending said line, means for connecting the operator's position to said line, means for sending impulses over said line, means at the operator's position for measuring the interval between the initiation of the call on said line and the instant when said impulses are transmitted, and means for signaling the operator if said 20 impulses are transmitted over the line before such line has been extended to a certain point.

21. In a telephone system, a line, an operator's position, means for extending said line, means for connecting the operator's position to said line, means for sending impulses over said line, means for measuring the interval between the initiation of a call on said line and the time when said line is 30 extended to a certain point, means for

measuring the interval between the initiation of said call and the instant when impulses are transmitted over said line, and means for signaling the operator if impulses are transmitted over the line before such 35 line has been extended to said point.

22. In a telephone system, a line, an operator's position, means for extending said line, means for connecting the operator's position to such line, means for sending impulses over said line, means at the operator's position for taking a record of the impulses transmitted, and means for signaling the operator if such impulses are sent over the line before said line has been extended to a 45 certain point.

23. In a telephone system, a line, an operator's position, means for extending said line, means for connecting the operator's position to said line, means for sending impulses over said line, means at the operator's position for making a graphic record of the impulses transmitted, and means for signaling the operator if impulses are sent over the line before said line has been extended 55 to a certain point.

In witness whereof, I hereunto subscribe my name this 18th day of October, A. D. 1921.

JOHN W. GOODERHAM.
